UNITED STATES PATENT OFFICE.

ARTHUR A. SCARLETT, OF CANTON, ILLINOIS, ASSIGNOR TO INTERNATIONAL HARVESTER COMPANY, A CORPORATION OF NEW JERSEY.

ROLLING COLTER FOR BRUSH BREAKERS.

Application filed January 30, 1926. Serial No. 84,816.

This invention relates to rolling colters for plows.

More particularly, the invention pertains to improvements in rolling colter constructions for plows used in breaking virgin land which presents a considerable variety of unusual obstacles such as roots, stones, stumps, etc. This type of plow is commonly known as a brush-breaker plow.

Among other objects, the invention is intended to provide a practical rolling colter construction of adequate strength and stability to meet the demands of the rough usage to which plows are subjected in breaking previously untilled land.

The invention will be clearly understood by reference to one illustrative construction embodying the invention, which is shown in the annexed drawings.

10 In the drawings:

Fig. 1 is an elevation of a portion of a plow having a rolling colter constructed in accordance with the teachings of this invention;

25 Fig. 2 is mainly a transverse vertical elevation and partially a transverse vertical section of the improved colter construction;

Fig. 3 is a plan;

30 Fig. 4 is an inclined sectional view taken on the line 4-4 of Fig. 1, looking in the direction of the arrows;

Fig. 5 is an enlarged elevation of the colter showing the arrangement of elements at the center of the colter disk; and

35 Fig. 6 is a sectional view of a part of the structure shown in Fig. 5, taken on the line 6-6 of Fig. 5.

In Fig. 3 of the drawings, the four-point support for the illustrative colter is indicated. Bars or struts 1, 2, 3 and 4 are attached at the points A, B, C and D to the parallel bars of the plow frame to afford such a support. The disk journal is advantageously braced against strains in every direction by these struts, which extend inwardly of the support points to the journal. This arrangement of elements is clearly represented in Fig. 3.

A pair of struts is located at each side of the plow. To afford effective journal supports and to promote desirable rigidity of the colter construction, these struts converge downwardly, as shown in Fig. 1 of

the drawings. They are also overlapped at their converged ends, and are joined by devices which will be hereinafter described.

Journal brackets 5 and 6 are rigidly secured to the inner surfaces of the struts 2 and 4, as indicated in Figs. 2 and 4. Their inner and lower ends are formed as annular journal supports having diametrically opposed pairs of sockets 7 and 8 formed by pairs of spaced lugs 9 and 10, which project from each annulus in a direction parallel to the axis about which the colter disk rotates.

For effectively holding the colter disk to its course and to prevent undesirable lateral swinging motion of the colter, the lower overlapped ends of the struts are connected by a structure which maintains them against inward as well as outward relative movements. This structure includes the tension rod or arbor bolt 11 and the compression sleeve 12 encasing the rod. When the burrs 13 on the ends of the rod are tightened, the opposite pairs of struts are securely gripped between the ends of the sleeve 12 and the respective burrs 13 in a manner which is clearly indicated in Fig. 4 of the drawings. Thus, there is provided a rigid, substantially U-shaped colter supporting frame which maintains the rotating colter parts in freely rotatable condition, the frame parts constituting a self-sustaining organization quite independent of the rotating elements.

Mounted so as to rotate around the sleeve 12 is a symmetrical compound hub structure for the disk 14. This hub structure comprises similar flanged hubs 15 having journal portions 16 shaped as frusto-conical bearing parts. Spaced from these bearing parts annular sand bands 17 are formed integral with each hub. Bolts 18 pass through the opposed flanges 19 of the hubs to secure them on opposite sides of the disk 14, as clearly shown in Figs. 4, 5 and 6 of the drawings.

Opposed journal caps 20, frusto-conical in shape, encase and rotatively support the hubs 15, the internal surfaces of these caps forming bearing surfaces to cooperate with the exterior bearing surfaces of the hubs. An appropriate clearance between the small ends of the journal caps and the sleeve 12 permits relative movements of these parts

so that the opposite journal caps may be self-aligning upon the insertion of the compound hub structure therein.

Diametrically opposed radial lugs 21, having lubrication devices 22, project from the raised annular portions 23 of the journal caps 20 and are so formed as to co-operate with the sockets 7 and 8 to afford a two-point support for each cap. This character 10 of support enhances the self-aligning feature of the journal caps and facilitates the assembling of the entire colter structure. By making the lugs 21 of such dimensions that there are slight clearances between their lateral faces and the corresponding walls of the sockets 7 and 8, the colter journal may adapt 15 itself to different positions of adjustment.

One end of the colter journal may be adjusted vertically and longitudinally by removing the burrs on bolts 29 which pass through the plow beam units 25 and 26 as well as through the upper ends of the struts 3 and 4. The projecting ends of these bolts may then be inserted through different ones 25 of a series of holes provided in these struts and the burrs replaced. When such an adjustment is made on only one of the struts, the lead of the colter disk is changed.

Adjustment of the opposite end of the 30 colter journal may be effected by sliding the U-shaped clamps 30 along the frame member 27 after these clamps are loosened. Pivot bolts 31 extending centrally from these 35 clamps permit the pivotal movement of the connected struts 1 and 2 as the clamps are moved along the frame.

Adjustment of any one of the struts may be such as to change the position of the lower 40 edge of the colter disk laterally with respect to the plow point 33 of the plow bottom 32. Thus the colter disk can be made to properly 45 cooperate with the plow under various soil conditions and under all conditions of wear or distortion resulting from long continued rough usage of the plow.

A suitable protective device, such as the 50 arcuate guard 34 extends up over the upper edge of the colter disk. This guard is secured at its ends to the plow frame, as clearly indicated in Fig. 1 of the drawings.

The illustrative colter construction adequately meets the demands of the rigorous service for which it is intended, eliminating 55 excessive vibration of the colter disk, effectively clearing a path for the plow point through different obstacles, and operating with a minimum increase of the draft required, considering the service performed.

The journal construction shown is constructed so as to facilitate proper lubrication of the bearing surfaces; it enables end thrusts and radial thrusts to be taken only by the lubricated parts; reduces wear upon the ends of the journal parts; adequately excludes dust and sand from the bearing surfaces; is mounted on a frame made rigid without the application of direct lateral pressure upon journal parts; and is so formed of duplicate parts that the advantage of standardization of parts obtains in its manufacture.

Obviously the present invention is not limited to the specific details of construction, arrangement and mode of operation shown in the drawings; since the same may be variously modified to suit different conditions or requirements.

I claim:

1. A rolling colter construction for plows comprising a plow beam structure, a rotating colter disk mounted beneath the frame on an axis transverse to said beam structure, a journal for said disk, a support for one end of the journal, two separate struts secured at their upper ends to one side of the beam structure and supporting the other end of the journal, means for adjusting each strut endwise relative to its point of securement to the beam structure so as to vary the length of the strut extending between its point of securement and the journal, and additional adjusting means for securing the upper ends of the struts at different positions longitudinally of the beam structure.

2. A rolling colter construction for plows comprising a plow beam construction, a colter disk rotatably supported thereby, a journal bearing construction for the disk, a support secured to one side of the plow beam construction and to one end of the bearing construction, two struts supporting the other end of the journal construction, means for securing the lower ends of struts to the bearing construction, a plow body having a plow point, a slidible fixture secured to the beam construction at the upper end of each strut whereby the spacing of the colter disk relative to the plow point may be changed by movement of said fixtures toward or from each other along the beam construction, and means for pivotally and adjustably securing the upper end of each strut to a fixture whereby the lead of the colter disk may be varied.

In testimony whereof I affix my signature.

ARTHUR A. SCARLETT,
